UNITED STATES PATENT OFFICE.

GUSTAVUS G. WAGNER, OF NEW YORK, N. Y., ASSIGNOR OF ONE-TENTH TO
FRANK L CRAWFORD, OF SAME PLACE.

PNEUMATIC CLOCK-REGULATOR.

SPECIFICATION forming part of Letters Patent No. 269,900, dated January 2, 1883.

Application filed April 13, 1882. (No model.)

To all whom it may concern:

Be it known that I, GUSTAVUS G. WAGNER, a citizen of the United States, residing at New York, in the county and State of New York, 5 have invented new and useful Improvements in Clock-Regulators, of which the following is a specification.

This invention relates to regulating clocks by gas-pressure, as in the manner described in Letters Patent of the United States granted to me November 9, 1880, or by the pressure of any suitable fluid; and it consists in the combination of a revolving tubular arbor gearing with the clock-movement, a compound revolving and sliding arbor carrying the minute-hand and extending through the tubular arbor, friction-disks fixed to the arbors, respectively, a balance-weight fixed to the arbor of the minute-hand, a pusher adapted to be actuated by fluid-pressure, and a means for connecting the pusher with the arbor of the minute-hand, so that whenever the pusher is actuated a reciprocating motion is imparted to the arbor of the minute-hand, and the friction-disks are brought 25 out of contact with each other a sufficient length of time to allow said arbor to follow the action of its balance-weight, whereby the minute-hand is set to a perpendicular position, thus starting from a determined point on the 30 clock-dial. A catch engaging the balance-weight insures the perpendicular position of the minute-hand.

This invention is illustrated in the accompanying drawings, in which Figure 1 represents a vertical cross-section. Fig. 2 is a rear view. Fig. 3 is a horizontal section on the line *x x*, Fig. 2.

Similar letters indicate corresponding parts.

The letter A designates the tubular revolving arbor; B, the compound revolving and sliding arbor; C, the minute-hand; D E, the friction-disks; F, the balance-weight, and G the pusher.

The arbor A gears with the movement of the 45 clock in any usual or suitable manner, and the friction-disk D is fixed thereto at one end. The arbor B carries the minute-hand C, and extends through the tubular arbor A, while the friction-disk E is fixed thereto in juxtaposition with the friction-disk D, as is common in clocks. The disk E, moreover, is geared

with an arbor, H, revolving loosely on the arbor B of the minute-hand and carrying the hour-hand I in the usual manner, to produce the proper motion of the hour-hand relatively 55 to the minute-hand. The balance-weight F is fixed to the arbor B of the minute-hand, near its rear end, such weight being made in the shape of an arm or pendulum.

In this example the pusher G is formed by 60 one side of a bellows, G', to which the gas or other fluid is admitted through a pipe, J, and the pusher is connected with the arbor B of the minute-hand by means of a main lever, K, which is fixed to a rock-shaft, L, at one end 65 and subjected to the action of a spring, N, having a tendency to keep the same in contact with the pusher at its opposite end, and of an auxiliary lever, O, which is fixed to said rock-shaft at one end and engages with the arbor B 70 at its opposite end. With the spring N is combined an adjusting-screw, P, for regulating its tension. The construction of the pusher G, however, is capable of modification, and other means can be used for connecting the same 75 with the arbor of the minute-hand, if seen fit.

In the normal positions of the parts the disks D E are in frictional contact with each other. When the gas or other fluid is admitted to the bellows G' under a high pressure the latter is 80 inflated and the pusher G displaces the lever K against the action of the spring N, the lever O at the same time acting on the arbor B of the minute-hand to slide the same in a forward direction. If the pressure of the gas is then 85 reduced, as to its normal standard, the lever K follows the action of the spring N, and by this means the parts are returned to a normal position. The arbor B of the minute-hand thus receives a reciprocating motion, during which 90 the friction-disks D E are brought out of contact with each other, thus releasing this arbor and allowing its balance-weight F to fall, whereby the minute-hand C is caused to take a perpendicular position. When the balance-weight 95 F has taken a lower position and during the forward motion of the arbor B of the minute-hand a catch, Q, engages the balance-weight and causes the same to take an exactly-perpendicular position, thus insuring that position 100 of the minute-hand. This catch Q consists of a lug having an angular notch, r, (see Fig. 3,)

the base of which is situated in a vertical plane intersecting the axis of the arbor B, and the balance-weight F is equipped with a ward, s, adapted to such notch. The construction of the catch, however, is capable of modification.

What I claim as new, and desire to secure by Letters Patent, is—

1. In a clock-regulator, the combination of a revolving tubular arbor gearing with the clock-movement, a compound revolving and sliding arbor carrying the minute-hand and extending through the tubular arbor, friction-disks fixed to the arbors, respectively, a balance-weight fixed to the arbor of the minute-hand, a pusher adapted to be actuated by fluid-pressure, and a means for connecting the pusher with the arbor of the minute-hand, the whole adapted to operate substantially as described.
- 15 2. In a clock-regulator, the combination of a

revolving tubular arbor gearing with the clock-movement, a compound revolving and sliding arbor carrying the minute-band and extending through the tubular arbor, friction-disks fixed to the arbors, respectively, a balance-weight fixed to the arbor of the minute-hand, a pusher adapted to be actuated by fluid-pressure, a means for connecting the pusher with the arbor of the minute-hand, and a catch adapted to engage the balance-weight for the purpose set forth, the whole adapted to operate substantially as described. 20 25 30

In testimony whereof I have hereunto set my hand and seal in the presence of two subscribing witnesses.
